US0D1048058S

(12) **United States Design Patent** (10) **Patent No.:** **US D1,048,058 S**
Kumar et al. (45) **Date of Patent:** **** Oct. 22, 2024**

(54) **DISPLAY SCREEN OR PORTION THEREOF WITH GRAPHICAL USER INTERFACE**

(71) Applicant: **ABBOTT DIABETES CARE INC.**,
Alameda, CA (US)

(72) Inventors: **Panganamala Ashwin Kumar**,
Oakland, CA (US); **Taylor May Charlesworth**, Oakland, CA (US);
Jessica Rose Floeh, Baltimore, MD (US); **Andrew M. Revoltar**, Burien, WA (US); **Natalie Margaret Clark**, Belmont, CA (US); **Daniel James Lorey**, Emerald Hills, CA (US); **Rene Maphorn Guerrero**, Alameda, CA (US)

(73) Assignee: **ABBOTT DIABETES CARE INC.**,
Alameda, CA (US)

(**) Term: **15 Years**

(21) Appl. No.: **29/853,251**

(22) Filed: **Sep. 14, 2022**

(51) LOC (14) Cl. **14-04**

(52) U.S. Cl.

USPC **D14/486**

(58) **Field of Classification Search**

USPC D14/485-495

CPC G06F 3/048-04897

(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a display screen or portion thereof with graphical user interface showing our new design.

The outer perimeter illustrated by dashed broken lines in the drawings illustrates a display screen or portion thereof and forms no part of the claimed design.

1 Claim, 1 Drawing Sheet
